UNITED STATES PATENT OFFICE.

GRANVILLE W. STAUFFER, OF PHOENIXVILLE, PENNSYLVANIA, ASSIGNOR
TO NATHAN P. STAUFFER, OF SAME PLACE.

COLLAR AND SHIRT PROTECTOR.

SPECIFICATION forming part of Letters Patent No. 636,864, dated November 14, 1899.

Application filed March 23, 1899; Serial No. 710,241. (No model.)

To all whom it may concern:

Be it known that I, GRANVILLE W. STAUFFER, a citizen of the United States, residing at Phoenixville, in the county of Chester and State of Pennsylvania, have invented certain new and useful Improvements in Collar and Shirt Protectors; and I do hereby declare the following to be a full, clear, and exact description of the same, reference being had to the accompanying drawings, forming part of this specification, and to the letters of reference marked thereon.

This invention relates to improvements in that class of protectors designed to be worn about the neck by individuals to protect the collar and shirt-front from becoming soiled or to give additional protection to the person of the wearer when worn with a low-cut vest or dress-suit; and the object of the invention is to simplify the device, render it light and efficient in use, and adapt it for use in connection with collars of any style or shape.

Referring to the accompanying drawings, Figure 1 is a perspective view of a device embodying my present improvements. Fig. 2 is a cross-sectional view showing its use in connection with a collar. Fig. 3 is a cross-sectional view in detail through the upper portion, showing the extensible box-plait. Fig. 4 is a detail perspective view of the retaining-band.

Like letters of reference in the several figures indicate the same parts.

The body portion A of the structure is preferably formed of silk or other light and tasty material and is adapted to be of a shape which will cover the shirt-front of the wearer and also drop down over the collar of the shirt and be long enough at the sides and back to protect the same.

From the drawings it will be noted that it takes the shape of a bib or depending curtain, open at the back at a and relatively long at the front. At the upper end it is provided with a band B, made in the form of a fabric tube, in which is slipped a curved or circular elastic strip C, Fig. 4. The ends of this strip are adapted to overlap, so as to give the band and upper portion of the protector a circular form conforming approximately to the neck

of the wearer and with the edges overlapped at the back to prevent the entry of dirt and give a wide range for different-sized persons. The inherent elasticity of the retaining-strip holds the parts in their proper shape about 55 the wearer's neck. The strip is perforated at C'. Thus there will be sufficient ventilation to prevent the neck of the wearer from becoming unduly warm, which will be more readily appreciated when it is understood that the 60 band fits down inside the shirt-collar.

The body of the material constituting the bib or curtain, from the band to the lower end of the front or widest portion, is formed with a relatively wide box-plait E, Fig. 1, having lines of stitches e down its edges and stitched together throughout the lower portion of its length; but at the upper portion the meeting edges at the back of the plait are left disconnected, whereby the material at 70 this point may be expanded to adapt itself to wings or collars of different shapes without otherwise distorting the shape of the device, and thus it will always present a neat and tasty appearance. To hold the lower end of the 75 bib or curtain down, I preferably weight the lower end in front, and as the most convenient way of accomplishing this end I preferably attach a small metallic weight G, Fig. 1.

In the use of the device the wearer will dis- 80 tend the curved retaining-strip and place the same around his neck and within the collar, the body portion of the protector extending from the band upwardly over the edge of the collar and then dropping down over the out- 85 side of the collar and over the shirt-front, as illustrated clearly in Fig. 2.

Obviously the curved retaining-strip may be made of steel or other inherently elastic substance which will retain its curve to fit 90 the wearer's neck, and the body portion may be made of any desired material and ornamented or padded to suit the taste of the wearer or the particular use for which it is intended—i. e., whether for summer, where 95 it is simply a guard against dirt and dust, or for winter wear, as a guard against the cold.

Primarily the device is intended for use of the traveling public or persons who wish to prevent the soiling of their linen, and for such 100

use it is preferably made of a washable material, and the band is provided with an opening through which the retaining-strip may be removed or inserted, thus adapting the device 5 to be readily washed or cleansed for subsequent use.

It will be noticed that the device is cheap, simple in its construction, readily adapts itself to any style or shape of collar, and when 10 not in use may be doubled up within the retaining-band and slipped into the pocket of the user in a neat compact form.

Having thus described my invention, what I claim as new, and desire to secure by Letters 15 Patent of the United States of America, is—

1. The herein-described article comprising the neckband, open at the back and having the curved retaining-strip therein with its ends overlapping and the body portion attached to the upper edge of said neckband, 20 narrow at the back and extending downwardly at the front, with a box-plait formed

centrally of such front portion, the sides of the upper portion of such box-plait being disconnected to permit the body portion to expand at the upper end to accommodate collars of different styles; substantially as described. 25

2. An article such as herein described, comprising a neckband having an elastic retaining-strip therein, with the ends overlapped to 30 conform to the neck of the wearer, said strip being perforated for ventilation and a textile body portion formed narrow and open in the back and relatively long and wide in front, said body portion being attached to the edge 35 of the neckband, whereby said band is adapted to fit within the collar of the wearer and the body portion to lie over the edge of the collar and protect the outer surface thereof and the front of the shirt; substantially as described. 40

GRANVILLE W. STAUFFER.
